UNITED STATES PATENT OFFICE

LEE B. GREEN, OF LAKewood, OHIO, ASSIGNOR TO THE BORDEN COMPANY, OF WARREN, OHIO, A CORPORATION OF OHIO

CENTRIFUGAL DRIER

Application filed November 16, 1928. Serial No. 319,929.

This invention relates to improvements in centrifugal driers for use in conjunction with clothes washing machines, and has to do not only with the construction of the drier itself but also with the mounting of the same upon a washing machine.

One of the objects of the invention is the provision of a mounting for a centrifugal drier of this class which will permit the drier basket with its load to adjust itself automatically to compensate for eccentricity in the center of gravity, thereby avoiding excessive vibration with its consequent evils.

Another object of the invention is the provision of means for suspending the drier basket entirely from above, whereby the mounting is simplified and the self-adjusting center of gravity feature rendered easy of accomplishment.

20 A further object is the hanging of the driving motor and the drier basket from a common flexibly supported mounting with the driving motor beneath the basket, whereby the mass of the motor on a relatively long lever arm opposes such vibrations as may be set up on account of whatever lack of rotational balance there may be in the basket and its contents.

Another object is the provision of a 30 mounting for use in conjunction with washing machines which will enable the operator to swing the drier casing around its supporting standard so that it may be drained by gravity into the washing machine tub, or into other tubs placed near-by without moving the washing machine itself.

Another object of the invention is the provision of a mounting in connection with the washing machine which will permit the 40 attachment interchangeable of a clothes wringer or a centrifugal drier.

Other objects and features of novelty will appear as I proceed with the description of those embodiments of the invention which, 45 for the purposes of the present application, I have illustrated in the accompanying drawings, in which

Fig. 1 is an elevational view, principally in section, showing the preferred form of 50 my invention;

Fig. 2 is a detail sectional view taken substantially on the line 2—2 Fig. 1;

Fig. 3 is a view similar to Fig. 1, showing a modified form of the invention;

Fig. 4 is a plan view illustrating an arrangement of the washing machine and drier for use in connection with stationary tubs; and

Fig. 5 is a further modification illustrating the centrifugal drier mounted for use as 60 a separate machine.

In the drawings I have illustrated at 10 a fragment of the tub of a washing machine, the tub being open at the top and provided with a cover 11. The washing machine comprises as a part of its framework a hollow post 12, hereinafter referred to as the wringer post. The post 12 is adapted to support a swinging wringer, such as is common and well known in the art, or the centrifugal drier of the present invention. In practice, the manufacturer produces three units, a tub unit, a wringer unit, and a centrifugal drier unit, shipping them separately to the dealer or the distributor who assembles them 75 to fill the orders taken. The arrangement is of benefit to the dealer as well as to the manufacturer, since it enables him to maintain a full stock without as much investment as would be required if he had to keep 80 in stock a tub unit for every wringer unit and drier unit.

In Fig. 1 I have indicated in dotted lines a wringer drive shaft 13 with a toothed upper end forming one element of a detachable coupling, the other element of which is carried by the wringer unit (not shown). In the wringer post 12 there are two separated annular bearings 14 and 15 adapted to receive with a nice rotating fit bearing surfaces on a vertical trunnion 16 which constitutes an integral depending part of a standard 17, in the case of the centrifugal drier, or a similar part in the case of a wringer. The standard 17, or the corresponding wringer part, as the case may be, is, therefore, rotatable about an axis coincident with the centers of the bearing surfaces 14 and 15. In order to take the vertical load and to increase the stability of the standard, the post 12 is formed at its up- 100

per end with an annular ledge 18, and the standard 17 is provided with a shouldered portion 19 which bears upon the said ledge.

The standard 17 has attached thereto or made integral therewith a pair of horizontally extending curved arms 20, to which is secured a drier casing 21 that is open at the top. The central portion of the bottom of the casing is also open and is provided with an upwardly extending flange 22 encircling the latter opening. In the bottom wall of this casing 21 I provide one or more drain openings 23, 23' through which the water removed by the centrifugal action may be discharged. Each drain opening is preferably provided with a valve. In the present instance I have illustrated for this purpose a slide plate 24 having a discharge opening 25 therethrough, the plate being pressed against a slide bearing 26 by spring means 27. A hooked portion 28 on the outer end of plate 24 serves as a handle for facilitating the opening and closing of the valve.

Above the level of the casing 21, the standard 17 carries an approximately horizontal arm 30. In the outer end of the arm 30 there is secured, by means of a pin 31 or otherwise, a flexible joint 32 capable of permitting motion in two directions at right angles to each other. Obviously, the particular character of this joint is not of importance here, and consequently will not be described in detail. The flexible joint 32 suspends by means of a pin 33, or otherwise, a tubular hanger 34 provided with a horizontal flange 35 at its lower extremity.

The centrifugal drier basket 36, which has a perforated cylindrical side wall, includes a central hub member 37, preferably in the form of a casting. The upper portion of this hub member rests upon an anti-friction thrust bearing 38 which is supported upon the flange 35 of the hanger 34, and a bushing 39 is interposed between the tubular hanger 34 and the hub member 37. The basket is, therefore, freely rotatable upon the hanger 34.

The drier of the present invention is driven by its own individual motor 40, which may be of usual construction except for the fact that the upper shell 41 of the motor casing is of special design in order to take screws 42, by means of which the motor is suspended from the flange 35 of the hanger 34. I employ a plurality of screws 42, although only one appears in the drawing. The shaft 43 of the motor is rotatable in bushings 44 and 45, carried by the motor casing. At its lower end the shaft 43 extends beyond bushing 45 and is keyed to a collar 46 upon which are formed integral arms 47. In the latter are mounted pivot pins 48 that pivotally support swinging weights 49 which are faced upon their outer curved surfaces with friction material.

A drive sleeve or cylinder 50 surrounds the motor 40 and is attached at its upper end to a flange 51 upon the casting 37. At its lower end the sleeve 50 is turned inwardly and is secured to a driving hub 52 having a smooth inner cylindrical surface adapted to be frictionally engaged by the weights 49 under the influence of centrifugal force. The lower portion of the driving hub 52 is offset inwardly and rotatably mounted upon the collar 46, a bushing 53 being interposed to reduce friction at times when there is relative movement between these parts.

Ventilation openings are provided in the sleeve 50 and in the motor casing in order to prevent overheating of the motor. As the sleeve 50 revolves at a rapid rate, I provide a guard 54 to prevent its coming in contact with anything during the operation of the drier, the guard being preferably flanged at its upper end and secured to the casing 21 by riveting, welding or other suitable means.

Electric current may be supplied to the motor 40 by means of a cable 55 which extends from the motor upwardly through the tubular hanger 34 and out through an opening 56 in the side thereof, and then through the hollow arm 30, standard 17 and post 12 to any convenient terminals, the conductors of the cable preferably extending through a switch inside the standard 17 that is controlled by a switch lever 57 on the side of the standard.

In the modification of the invention illustrated at Fig. 3, the mounting of the drier is substantially like that above described, comprising the wringer post 12, standard 17, curved arms 20 for supporting the drier casing, extension arm 30, and flexible joint 32 depending therefrom. The drier casing 21' is also similar to the casing 21, although of somewhat different design. In this modification, however, the hanger 60 extends through the electric motor 61 and carries the fixed armature coils of the motor; that is to say it takes the place of the ordinary motor shaft. The field of the motor, to which the casing 62 is attached, rotates. At its upper end this casing is provided with an extension 63 which supports a drier basket 64. The extension 63 is of annular shape, but is provided with perforations between the bottom of basket 64 and the bottom of casing 21' in order to permit free circulation of air. The upper end of the casing 62 is closed or partially closed by a bowed cover plate 65 which is welded or otherwise fastened to the flared extension 63 and which carries at the center a bushing holder 66 containing a bushing 67 that rotates upon the cylindrical hanger 60. The motor casing also has a rotatable bearing (now shown) upon the lower end of the hanger 60. The motor commutator is located at the lower end of the motor, and the current is conducted to it by a flexible cable 68 extend-

ing through a metal tube 69 of goose neck form, which is employed for the protection of the cable. Sufficient slack is provided in the exposed portion of the cable to accommodate any movement of the hanger upon its flexible mounting.

In order to keep the clothes within the rotating basket 64 away from the stationary hanger 60, and in order to protect them from any lubricant which may collect on the hanger, the latter is enclosed by an encircling sleeve 70, welded to the basket 64 around the central opening 71 therein. The upper portion of this sleeve is preferably provided with ventilation openings 72 which cooperate with the opening 71 and the perforations in extension 63 to permit circulation of air.

In Fig. 4 I have illustrated the arrangement of the combined washing machine and centrifugal drier which is recommended with respect to a pair of stationary tubs. The latter are indicated at 73 and 74. In this figure the drain opening 23 is in position to discharge liquid from the casing 21 into the tub 74. By swinging the drier standard 17 through a small angle this drain opening can be brought into position above the tub 73. By swinging the drier through a somewhat greater angle in the same direction, the drain opening 23' can be brought into position to discharge liquid into the tub 10 of the washing machine. This swinging of the drier accomplishes two important functions, first, it brings the drier into close proximity to the tub from which it is to be loaded, and, second, it provides means for delivering the liquid removed from the clothes into the proper container without the use of a pump and other associated parts. The employment of a separate motor for the drier is not detrimental, because its cost is made up largely, if not entirely, by the saving in driving connections, and because it provides a highly efficient silent drive.

Where it is desired to provide a centrifugal drier as a separate machine, my drier unit in either of its above described forms may be employed, but in such cases I prefer to modify the standard somewhat, as indicated at 17' in Fig. 5. As shown in this figure the standard 17' is secured, by means of rivets or the like, to a ring 80 of angle bar material upon which the bottom of the casing 21 rests, the motor 40 extending downwardly through the opening in the ring. The ring 80 may be mounted at the upper ends of channel bars 81 or the like, these bars being attached at their lower ends to a second ring 82 that is supported upon casters 83. For the sake of appearance and in order to further strengthen the machine, a sheet metal skirt 84 may be placed around and secured to the rings 80 and 82 and the bars 81.

The operation of the invention will be clear from the above description of its construc-

tion. When a batch of clothes has been washed in the washing machine, the operator grasps the arm 30 and swings it clockwise, as viewed in Fig. 4, until the guard 54 encounters the side of tub 10. The casing 21 is then partially overhanging the tub 10, and the drain opening 23' is positioned above the tub. The basket 36 is now loaded from the tub. When the loading is complete, the valve which controls the drain 23' is opened and the switch lever 57 is thrown to start the motor 40. As the shaft 43 gets up speed the weights 49 begin to press upon the driving hub 52 to transmit driving force thereto. However, the weighted basket 36 possesses considerable inertia, and there is consequently much slippage between the parts 49 and 52 at the start, this being gradually lessened as the speed of the basket approaches that of the motor, until finally they turn at the same speed and slippage is eliminated. The suds in the clothes are now thrown outwardly by centrifugal force through the openings in basket 36 against the side wall of the casing 21, and the suds are then drained out of the casing through the opening 23' back into the washing tub.

The operator then swings the arm 30 back in an anti-clockwise direction until the drain opening 23 extends above the tub 74, as illustrated in Fig. 4. The clothes in the basket 36 are now emptied into the tub 74, where they are rinsed. The drain opening 23' is then closed and the drain opening 23 opened. Then the clothes are returned to the basket 36 and the latter is rotated to remove the rinsing water which drains back into tub 74. Now the arm 30 is swung a short distance clockwise to bring the drain opening 23 above tub 73, in which the bluing water is located. The clothes are then emptied into the bluing water and again returned to the drier basket, which is again rotated to remove the bluing water, the latter draining back into the tub 73. In the meantime, of course, a second batch of clothes may be in process of being washed in the tub 10. The cycle of operations is repeated for each batch.

The form of the invention illustrated in Fig. 3 functions in substantially the same way as that shown in Fig. 1, the basket 64 and the motor 61 being both suspended upon the hanger 60, which is free to adjust itself upon the flexible joint 32. However, the form of the invention illustrated in Fig. 1 is somewhat preferred in view of the fact that it utilizes ordinary rotating-shaft electric motors, which may be purchased at a lower cost than the special rotating-field motors that are required in the modification of Fig. 3.

Although in the present disclosure I have illustrated and described with considerable particularity certain preferred embodiments of the invention, I desire it to be understood that such detailed disclosure is primarily for

purposes of illustration and is not to be construed as a limitation upon the scope of the invention.

Having thus described my invention, I claim:

- 5 1. In a centrifugal clothes drier, a support, a non-rotatable hanger carried thereby, said hanger comprising a flexible joint, a drier basket rotatably suspended upon said hanger, a motor casing secured to said hanger below said basket, said motor having a vertical rotor with a shaft extending downwardly through said casing, and a driving connection extending from the lower end of said shaft upwardly around said motor casing and attached to said basket.
- 10 2. In a centrifugal clothes drier, a support comprising a hollow standard rotatable to various angular positions, a hollow arm extending laterally from said standard, a tubular hanger non-rotatably suspended from said arm, a drier basket rotatably suspended from said hanger, an electric motor also suspended from said hanger, and an electric conductor extending through said standard arm and tubular hanger down to said motor.
- 15 3. In a centrifugal clothes drier, a support, an outer container fixed thereto, said container having a central opening in the bottom thereof, a non-rotatable hanger carried by said support centrally of said container, a drier basket rotatably suspended upon said container, a driving motor also suspended from said hanger within the opening in said container, a driving connection extending from the lower end of said shaft upwardly around said motor casing and attached to said basket, and a circular guard depending from the bottom of said container around said opening spaced from said driving connection.
- 20 4. In a centrifugal clothes drier, a support, a non-rotatable hanger carried thereby, said hanger comprising a flexible joint, a drier basket hung from said hanger and rotatably supported thereon, a motor of the vertical shaft type hung from said hanger below said basket, and means for operatively connecting said basket with the shaft of said motor at the lower end thereof.
- 25 5. In a centrifugal clothes drier, a support, a non-rotatable mounting carried thereby, said mounting comprising a flexible joint, a drier basket supported exclusively upon said mounting, a motor also supported exclusively upon said mounting with its center of mass below the center of mass of the basket, and means comprising a centrifugal clutch for operatively connecting the lower end of the shaft of said motor with said basket.
- 30 6. In a centrifugal clothes drier, a support, a non-rotatable hanger carried thereby, said hanger comprising a flexible joint, a drier basket hung from said hanger, a motor also hung from said hanger with its center of mass below the center of mass of the basket, and

means for operatively connecting the lower end of the shaft of said motor with said basket, such means comprising a centrifugal clutch.

7. In a centrifugal clothes drier, a support, a non-rotatable hanger carried thereby, said hanger comprising a flexible joint, a drier basket hung from said hanger and rotatably supported thereon, a driving motor of the vertical shaft type hung from said hanger below said basket, a sleeve attached to said basket and surrounding said motor, and means for operatively connecting said sleeve with the shaft of the motor at the lower end thereof.

In testimony whereof, I hereunto affix my signature.

LEE B. GREEN.
